US0D1089500S

(12) **United States Design Patent** (10) Patent No.: **US D1,089,500 S**
(45) Date of Patent: ** Aug. 19, 2025

(54) **CLIMBING FRAME**

(71) Applicant: **FDS GmbH**, Hamburg (DE)

(72) Inventor: **Sarah Anderson**, Hamburg (DE)

(73) Assignee: **FDS GmbH**, Hamburg (DE)

(**) Term: **15 Years**

(21) Appl. No.: **29/903,835**

(22) Filed: **Sep. 28, 2023**

(51) LOC (15) Cl. **21-03**

(52) U.S. Cl.

USPC **D21/826**

(58) Field of Classification Search

USPC D21/484, 811, 814, 818, 826, 827

CPC . A63B 9/00; A63B 2208/12; A63B 2009/006;

(57) **CLAIM**

The ornamental design for a climbing frame, as shown and described.

DESCRIPTION

FIG. 1 is a first perspective view of a climbing frame showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
